UNITED STATES PATENT OFFICE.

EDWIN D. STALFORT, OF BALTIMORE, MARYLAND.

CUSHION-HEEL.

1,307,990.

Specification of Letters Patent. Patented June 24, 1919.

Application filed April 29, 1918. Serial No. 231,454.

To all whom it may concern:

Be it known that I, EDWIN D. STALFORT, a citizen of the United States, residing at Baltimore, in the State of Maryland, have 5 invented new and useful Improvements in Cushion-Heels, of which the following is a specification.

This invention relates to cushion heels and has for its object the provision of a heel 10 which is flat upon the central portion of its top and bottom whereby a flat bearing surface is always maintained and which has its top and bottom faces provided with upwardly inclined portions forming a saucer edge whereby a suction effect is produced when the heel is applied to a shoe, and whereby gaping of the edges from the shoe 15 will be prevented.

An important object is the provision of a heel 20 of this character in which the securing nails are disposed at the edges of the central flat portion whereby ample space will be provided between the securing members and the edges of the heel to permit trimming 25 into a wide variety of sizes without impairing the advantageous construction of the flat portion having saucer edges.

Another object is the provision of a heel 30 of this form which will be of absolutely uniform thickness throughout and which has its saucer edge rolled, that is: longitudinally curved, this curvature not affecting the central flat portion.

An additional and important object is the 35 provision of a heel of this character which has the upper edge of its breast straight and lying in a horizontal plane in close contact with the shoe lifts whereby downward buckling at the breast will be positively prevented on account of the straight bearing thus provided.

With these and other objects and advantages in view, the invention consists in the detailed construction to be hereinafter more 45 fully described and claimed and illustrated in the accompanying drawing in which:—

Figure 1 is a side elevation of a portion of a shoe showing my heel, partly in section, applied thereto in position preliminary to 50 securing it,

Fig. 2 is a similar view, showing the heel fastened in place,

Fig. 3 is a plan view of the heel,

Fig. 4 is a cross-sectional view detached,

Fig. 5 is a longitudinal sectional view, 55
Fig. 6 is a plan view of a slightly modified form, and

Fig. 7 is a sectional view therethrough. Referring more particularly to the drawing the letter A designates a shoe heel to 60 which my cushion heel B is adapted to be applied.

My heel comprises a body 10, formed of rubber or other suitable resilient material having a central portion 11 which is absolutely flat upon its top and bottom. Both the top and bottom faces of the body 10 are provided with outwardly and upwardly inclined portions 12 and 13 which form a saucer edge. The inclined portion 12 is longitudinally curved as shown and the portion 13 terminates in the breast 14 of the heel. The upper edge 15 of the breast is a straight line so that it will bear flatly against the shoe heel A when applied. The inclination 70 of the portions 12 and 13 is the same at the top and bottom surfaces of the body so that the heel is consequently of uniform thickness throughout.

Metallic washers 16 are embedded in the 80 body 10 at the edges of the central flat portion and have central apertures alining with holes 17 in the body for receiving the nails 18 by means of which the heel is secured upon a shoe.

When the heel is applied to a shoe and secured in place by the nails or other suitable fastenings, the central flat portion 11 will be drawn into engagement with the shoe heel and the bottom face of my heel will be 90 flat. The provision of the straight upper edge 15 of the breast gives a flat bearing for the heel which prevents creeping and which renders any downward buckling of the breast impossible. The provision of the central flat portion 11 is very important for the reason that a flat surface bearing upon the ground is insured even though the nails might become loose so as to allow the heel to draw away from the shoe.

A heel constructed as shown in Figs. 1 to 5 has a greater or less suction when applied, but in order to increase the suction effect I have modified the structure as shown in Figs. 6 and 7. In this form, I have shown 105 the flat portion 21 as provided with a circular suction cup 22 which extends above the top of the flat portion and which is sur-

rounded by a groove or channel 23. When this form is applied to a shoe the cup 22 will be flattened out and will have a suction effect assisting in maintaining the heel in position.

From the foregoing description and a study of the drawing it will be apparent that I have thus provided a cushion heel which has all the advantages of the concave and flat types combined in a single structure, which will fit snugly against a shoe heel without gaping or buckling at the edges, and which will always present a flat surface to the ground even though the securing means might become loosened.

While I have shown and described the inclined portion 12 as curved longitudinally, it will be readily understood that I reserve the right to form the inclined portions as

having their upper edges all lying in the same horizontal plane.

Having thus described my invention I claim:—

1. A cushion heel comprising a body having a flat central portion and a peripherally extending upwardly and outwardly inclined portion constituting a saucer edge, said saucer edge being curved longitudinally and having its forward upper edge straight.

2. A cushion heel comprising a body having a flat central portion and a peripherally extending upwardly and outwardly inclined portion constituting a saucer edge, said saucer edge being curved longitudinally and having every point of its forward upper edge lying in a horizontal plane.

In testimony whereof I affix my signature,
EDWIN D. STALFORT.
